Primary Examiner — Mimosa De(74) *Attorney, Agent, or Firm* — Westerman, Hattori, Daniels & Adrian, LLP(57) **CLAIM**

The ornamental design for seats for airline passengers, as shown and described.

DESCRIPTION

FIG. 1 is a first perspective view seats for airline passengers, showing our new design;

FIG. 2 is a second perspective view thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof; and,

FIG. 9 is a reference view showing used seat seats for airline passengers view thereof.

The broken lines in the drawings illustrate portions of seats for airline passengers that form no part of the claimed design.
